CABLE EQUALIZER

Thomas J. Wilson, Pittsburgh, Pa.

Application June 2, 1934, Serial No. 728,767

6 Claims. (Cl. 187—1)

The invention relates to a cable equalizer and more especially to elevator cable equalizers.

The primary object of the invention is the provision of a device of this character wherein the same, when installed with elevator equipment, will equalize the tension of the lifting cables of the traction type of elevators, such equalization being important or a factor in the length of service of the cables and also preventing excessive wear of sheave grooves.

Another object of the invention is the provision of a device of this character, wherein stuffing boxes are entirely eliminated, there being one point of possible leakage, namely, the cup packing of each piston, the lifting bolts of the device being either square or elliptical in shape, these fitting into similarly designed guide holes of cylinder block to prevent twisting of the equalizer bars and thus throwing them out of alignment, and, additionally, the load is not sustained on the equalizing device but rather the entire load is suspended from the shackle or lifting bolts, there being a minimum number of moving parts in the device.

A further object of the invention is the provision of a device of this character, wherein it involves a combination of leverage and hydraulic principles, the sensitiveness of the device being to compensate instantaneously any unequal stretch in cables, therefore, the movement of any piston will be so slight as to render wear on the parts practically nil, the device being adapted to prevent bobbing or teetering of the lift body when descent or ascent is interrupted.

A still further object of the invention is the provision of a device of this character which is simple in construction, thoroughly reliable and efficient in its purpose, strong, durable, and inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a plan view of the device constructed in accordance with the invention, the same being partly in section.

Figure 2 is an end elevation thereof, the same being partly broken away.

Figure 3 is a side elevation, the same being partly broken away.

Figure 4 is a sectional view on the line 4—4 of Figure 1 looking in the direction of the arrows.

Similar reference characters indicate corresponding parts throughout the several views in the drawings.

Referring to the drawings in detail, the pressure chamber and plunger construction, a number being shown in cooperative relation to each other, constitutes an equalizing suspension device for elevators and consists of a casing 10 having formed therewith a plurality of piston cylinders 11, these being preferably arranged in spaced parallel rows longitudinally of said casing and open through the top thereof, the cylinders being equally spaced from each other in the plurality. Operating within the cylinders 11 are pistons 12, their stems 13 being extended upwardly through guide bushings 14 removably threaded in the upper open ends of said cylinders. The cylinders 11, at their bottoms 15, have the ports 16 common to a liquid way 17, there being the required number of ways corresponding to the rows of cylinders and intercommunicative through a passage 18, one of the ways 17 being connected with a liquid reservoir 19 for the delivery of the liquid 20. The reservoir has fitted therewith a hand operated cut-off valve 21 and a check valve 22, these valves being arranged or located as shown in Figures 1 to 3 inclusive of the drawings. The passage 18 opens through one side of the casing 10 and is closed by a removable plug 23, so that the said passage and ways 17 can be drained, as the occasion may require.

Passed through the casing 10 are the lifting bolts 24, these being secured to a sub-base 25 through the medium of nuts 26, and the upper ends of these bolts are formed with forked heads 27 carrying pivots 28 for the equalizer levers 29, these being received in the heads 27, while the outer long end portions of said levers, through the medium of the pivots 29', are connected with the bifurcated upper ends 30 of the stems 13 of the pistons 12 and the inner shorter ends of said levers by the pivots 31 are connected through the medium of the couplings 32 with the lifting cables 33 for the elevator (not shown).

Any additional or replenishing of liquid to the reservoir 19 is had through the medium of a plunger type hand pump (not shown) and separate from the device.

As has been stated, the purpose of the device is to equalize the tension of the lifting cables

35

40

45

50

55

32, the compensation or equalization being had through the medium of the pistons 12 coating with the liquid 17 in the cylinders 11. When the load is unequally distributed in one or more of 5 the lifting cables, the compensating pistons 12 will be compressed, thus exerting a downward pressure on the body of liquid 17. This additional pressure imparts an upward movement to the one or more compensating pistons 12. 10 This upward movement of the pistons causes a counter movement to the equalizer levers 29 which pulls the slacken cable or cables taut.

In the event of sudden loss of pressure, the 15 equalizer levers 29 will, at their outer ends, be lowered against the top of the casing 10 and the load will be sustained by the lifting bolts 24 which are designed for such an emergency.

What is claimed is:

1. An equalizer of the character described 20 comprising a casing forming a plurality of piston cylinders arranged in rows, pistons working in said cylinders, said casing having fluid passages common to the cylinders, means for supplying fluid to said passages to maintain a 25 determined content therein, lifting means passed through the casing and fixed with respect thereto, equalizer levers pivotally supported in said lifting means and having connection with the pistons, and lifting cables having connection 30 with said levers.

2. An equalizer of the character described comprising a casing forming a plurality of piston cylinders arranged in rows, pistons working in said cylinders, said casing having fluid passages common to the cylinders, means for supplying fluid to said passages to maintain a 35 determined content therein, lifting means passed through the casing and fixed with respect thereto, equalizer levers pivotally supported in said lifting means and having connection with the pistons, lifting cables having connection with 40 said levers, and a fluid reservoir included in said fluid supply means.

3. An equalizer of the character described 45 comprising a plurality of piston cylinders, pistons working within said cylinders, means for supplying liquid to the cylinders and maintained

at a determined content thereof, lifting bolts related to the cylinders, equalizer levers pivotally supported by said bolts and having connection with the pistons at one side of the bolts, and lifting cables connected with said levers at the 5 opposite side of the bolts.

4. An equalizer of the character described comprising a plurality of piston cylinders, pistons working within said cylinders, means for supplying liquid to the cylinders and maintained 10 at a determined content thereof, lifting bolts related to the cylinders, equalizer levers pivotally supported by said bolts and having connection with the pistons at one side of the bolts, lifting cables connected with said levers at the 15 opposite side of the bolts, and a casing having the piston cylinders built therein and forming a receptacle for said liquid.

5. An equalizer of the character described comprising a plurality of piston cylinders, pistons working within said cylinders, means for supplying liquid to the cylinders and maintained 20 at a determined content thereof, lifting bolts related to the cylinders, equalizer levers pivotally supported by said bolts and having connection with the pistons at one side of the bolts, lifting cables connected with said levers at the 25 opposite side of the bolts, a casing having the piston cylinders built therein and forming a receptacle for said liquid, and means for drawing off the liquid within the receptacle.

6. An equalizer of the character described comprising a plurality of piston cylinders, pistons working within said cylinders, means for supplying liquid to the cylinders and maintained 35 at a determined content thereof, lifting bolts related to the cylinders, equalizer levers pivotally supported by said bolts and having connection with the pistons at one side of the bolts, lifting cables connected with said levers at the 40 opposite side of the bolts, a casing having the piston cylinders built therein and forming a receptacle for said liquid, means for drawing off the liquid within the receptacle, and means for replenishing the supply of liquid within the 45 receptacle.

THOMAS J. WILSON.
